UNITED STATES PATENT OFFICE

WILLIAM J. TAIT, OF JERSEY CITY, NEW JERSEY.

BALUSTER.

SPECIFICATION forming part of Letters Patent No. 278,200, dated May 22, 1883.

Application filed January 9, 1883. (No model.)

To all whom it may concern:

Be it known that I, WILLIAM J. TAIT, of Jersey City, in the county of Hudson and State of New Jersey, have invented certain new and useful Improvements in Balusters for Railings, of which the following is a full, clear, and exact description.

The object of my invention is to provide certain new and useful improvements in balusters for stair and other railings, whereby the cost of making and fitting the balusters will be reduced, and the balusters will be held in place more securely.

Reference is to be had to the accompanying drawings, forming part of this specification, in which similar letters of reference indicate corresponding parts in all the figures.

Figure 1 is a bottom perspective view of the lower end of a baluster of the usual construction. Fig. 2 is a bottom perspective view of one end of a step provided with dovetail mortises for receiving the dovetailed tenons of balusters of the usual construction. Fig. 3 is a bottom perspective view of one of my improved balusters. Fig. 4 is a bottom perspective view of one end of a step provided with circular segmental mortises for receiving the circular dovetailed tenons of my improved balusters. Fig. 5 is a plan view of the under side 30 of one end of a step on which one of my improved balusters is secured.

Heretofore it has been customary to turn balusters cylindrical at the lower end or leave them square, and to cut an annular groove 35 into the said cylindrical part a short distance above the lower end of the same, to indicate how long the tenon is to be and insure an equal length of all balusters above the tenon—*i. e.*, above the tops of the steps or base on 40 which the balusters are secured. In this shape the balusters were delivered by the turner to the stair-builder who then formed the dovetailed square tenon A on the lower end of the baluster B. Square dovetailed mortises 45 C were formed in the end of the step D or in any other base, and the tenons B were driven into the mortises C, whereupon the projecting parts of the tenons were cut off by means of a chisel or other implement flush 50 with the end of the step. Then an end strip was nailed on the end of the step to cover

the outer sides of the tenons. The tenons were not all made of exactly the same shape, and did not fit very exactly in the mortises, and consequently the balusters were not held 55 very firmly in the step; and, furthermore, they were quite expensive, as considerable labor was required to form the square dovetailed tenons A.

In order to obviate the above difficulties, I 60 provide the balusters B' with a circular dovetailed tenon, A'—that is, a tenon in the shape of a truncated cone with the top in contact with the bottom of the balusters, which truncated-cone tenon is formed on the balusters 65 by the turner at the same time that the bolster is turned, thus obviating the forming of the tenon by the stair-builder, whereby much labor, time, and money is saved. The truncated-cone tenon A' can be driven into a square 70 or oblong dovetail mortise, C; but preferably I provide segmental or circular dovetail mortises C', which are bored into the steps D' by means of a conical auger-bit applied on the bottom of the step. After the tenon A' has 75 been driven into either the mortise C or C' the part projecting beyond the end of the step is cut off flush with the end of the step by means of a chisel or other suitable implement, and then the end strip, E, is nailed on the end of 80 the step. The flat side of the tenon A', which flat side is formed by cutting the tenon off flush with the end of the step, is in contact with the inner side of the end strip, E, and thus the baluster is prevented from turning. If 85 the tenon A' is driven into a square or oblong mortise, the lower end of the cylindrical part of the balusters covers the triangular openings formed by the corners of the mortise and the round sides of the tenon.

My improved baluster can be fitted much more rapidly and more accurately in the mortises than the usual square tenons, and thus the baluster is held better, and the cost is much less.

The above-described improved balusters can be used for stair, office, and other railings.

I am aware that balusters have been constructed with cylindrical tenons which were glued in cylindrical mortises; but that I do 100 not claim, as my improved balusters are not held in place by glue, but by the dovetailed

shape of the tenons, and glue, if used on my dovetailed balusters, is only to give additional firmness.

Having thus described my invention, what I claim as new, and desire to secure by Letters Patent, is—

1. A baluster constructed with a circular dovetailed or inverted truncated-cone shaped tenon at its lower end, substantially as herein shown and described, and for the purpose set forth.

2. The combination, with a stair-step or other base provided with dovetailed mortises, of a baluster having a circular dovetailed tenon at its lower end, which tenon is held in the mortise substantially as herein shown and described, and for the purpose set forth. 15

WILLIAM J. TAIT.
